CLAIM

The ornamental design for a sponge mop, shown and
described.

DESCRIPTION

FIG. 1 is a perspective view of a sponge mop showing
my new design, the undisclosed sides of the handle
being unornamented;

FIG. 2 is an enlarged perspective view thereof shown
without the handle for clarity of illustration only;

FIG. 3 is a top plan view thereof;

FIG. 4 is a bottom plan view thereof, the mop being
positioned at a forward tilt;

FIG. 5 is a left side elevational view thereof; the oppo-
site side being a mirror image;

FIG. 6 is a front elevational view thereof; and,

FIG. 7 is a rear elevational thereof.

FIG. 1
